Assignee to

George W. Nichols of New York, N.Y.

Letters Patent No. 1060, dated, Fe^r 26, 1838.

The schedule referred to in these Letters Patent and making part of the same.

To all persons to whom these presents shall come:

Be it known, that J. J. Ball of Boston in the County of Suffolk, and State of Massachusetts, have invented or produced a new and useful design for a Hattole of Henry Clay, and I hereby declare that the said new design is fully described and represented in the following spe-

cification and accompanying drawings, to which reference is hereinafter made.

The figure of the accompanying plate of drawing is a front perspective view of my new design for a Statuette of Henry Clay.

In the figure of Henry Clay is represented as standing with his feet turned outward, his coat a or unbuttoned, vest is buttoned, and holding in both hands a manuscript or scroll c. At the side is a pedestal, over which is thrown loosely a mantle f.

Having thus described my new design, I shall state my claim as follows:

What I claim as my new invention or production and desire to have secured to me by Letters Patent, is the new design herein described and represented in the drawings, for a Statuette of Henry Clay.

Given Witness,

J. M. G. Joseph Gaville.
Albert W. Brown.
